UNITED STATES PATENT OFFICE.

JOHN D. CURTIS, OF WORCESTER, MASSACHUSETTS, ASSIGNOR TO THE WASHBURN & MOEN MANUFACTURING COMPANY, OF SAME PLACE.

APPARATUS FOR AUTOMATICALLY STOPPING MACHINES FOR MAKING WIRE FENCING.

SPECIFICATION forming part of Letters Patent No. 340,198, dated April 20, 1886.

Application filed November 18, 1885. Serial No. 183,177. (No model.)

To all whom it may concern:

Be it known that I, JOHN D. CURTIS, a citizen of the United States, residing at Worcester, in the county of Worcester and State of Massachusetts, have invented certain new and useful Improvements in Apparatus for Automatically Stopping Machines for Making Wire Fencing; and I do hereby declare that the following is a full, clear, and exact description thereof, which, in connection with the drawings forming a part of this specification, will enable those skilled in the art to which my invention belongs to make and use the same.

My invention relates to an apparatus or mechanism to be used in connection with machines for making wire fencing, especially designed to be used in connection with machines for making barbed fencing of any old and well-known construction, for the purpose of automatically stopping the machine, in case of any obstruction in or on the main wire or wires, or either of them, before they enter the machine, (as a splice knot or snarl,) which would prevent them from freely passing through the machine, or allowing the machine to operate in a proper manner in applying the barbs or making the fencing.

My invention consists in the combination, with a machine for making wire fencing or barbed fencing, of a device placed at the rear end of the machine, so as to be acted upon by the wire or wires before they enter the machine, and mechanism for automatically shipping the driving-power or stopping the machine, operated by said device at the rear of the machine, in the manner to be hereinafter fully described and set forth.

Referring to the drawings, Fig. 1 is a side view, partly in section, of my improved automatic stopping apparatus, and of a barbing-machine, and a portion of a twisting and spooling machine, operated independently by separate counter-shafts and belt-connection, and in connection with which my automatic stopping apparatus is used. Fig. 2 is a rear elevation of the barbing-machine and the automatic stopping apparatus shown in Fig. 1, looking in the direction of arrow x , same figure. Fig. 3 is a horizontal section on line a , b , Fig. 2, looking in the direction of arrow y , same figure, showing plan of belt-shippers; and Fig. 4 is a plan of the rocking-lever holder, to be hereinafter described, looking in the direction of arrow w , Fig. 1.

In the accompanying drawings I have shown only such parts of a common and well-known form of barbing-machine and of a twisting and spooling machine as will be essential for the proper understanding of my invention and the operation thereof, when used in connection therewith, for automatically stopping the same, in case of any obstruction on the main wire or wires, or either of them, before entering the barbing-machine.

The barbing and the twisting and spooling portion of the barbed-fence machine shown in the drawings are in this instance made separate from each other, and operated by belt-connection on independent counter-shafts, both counter-shafts being driven by belt-connection with one main shaft.

The barbing and the twisting and spooling portion of the barbed-fence machine shown in the drawings are in this instance made separate from each other, and operated by belt-connection on independent counter-shafts, both counter-shafts being driven by belt-connection with one main shaft.

If preferred, the barbing portion and the twisting and spooling portions of the machine for making the barbed fencing may be all made in one machine, as in the case of Letters Patent No. 187,776, to H. W. Putnam, so that the automatic stopping of the barbing portion of the machine will also stop the twisting and spooling portion of the machine. In that case, as will be readily understood by those skilled in the art, the devices shown in the drawings for shipping the belt that operates the twister and spooler may be dispensed with, as it will only be necessary to employ the devices shown for shipping the belt that operates the barbing portion of the machine to stop the same, and simultaneously to stop the twister and spooler, and this without departing from the principle of my invention, for it will be readily understood by those skilled in the art, by referring to the drawings, and in connection with the description to be hereinafter given, that the belt-shipping device of the twister and spooler shown in the drawings is simply a duplicate of the belt-shipping device of the barbing portion of the machine, both being operated together by the device placed at the rear end of the barbing-machine, through which the main wire or wires pass in the manner to be hereinafter fully described.

In the drawings, A represents a barbing.

machine, in this instance operated by a belt, B, passing around the driving-wheel C, secured upon the main shaft C' of the machine, and over a pulley, D, secured upon the counter-shaft E, which is supported in this instance by means of angle-hangers or supports e, secured to the under side of the beam or plank d. In the outer ends of the angle-hangers e is supported the sliding rod e (see Fig. 3) for shipping the belt from the fast to the loose pulley in the usual manner.

The barbing-machine shown in the drawings is designed to apply a barb to one of the two main wires which pass through the machine, the free wire being twisted with the barbed wire after the barb has been applied to the wire by means of the twisting and spooling machine, a portion of which is shown in the drawings, F being the frame, and G the revolving shaft supported therein, carrying upon its outer end, toward the barbing-machine, the twisting and spooling device, of any well-known form and construction, which is not shown in the drawings, said shaft F being operated by a belt, H, passing around a pulley, I, secured thereto, and over a pulley, J, secured upon the counter-shaft K, which is supported in this instance by means of angle-hangers or supports f, which also support a sliding rod, g, for shipping the belt from the fast to the loose pulley, as above described in connection with counter-shaft E. The counter-shafts E and K have each a fast and loose pulley, L and M, thereon, and are driven by belts N and O, which pass around pulleys on the main driving-shaft, which is not shown in the drawings.

The belt N, for driving the counter-shaft E, is shipped from the fast pulley L to the loose pulley M by means of the lever-arm P, pivoted at its upper end to the support h, and attached to the sliding rod e, a guide, i, secured to the rod e, passing over the belt N, all as clearly shown in Fig. 2 of the drawings.

The belt O, for driving the counter-shaft K, is shipped in the same manner as the belt N, except that the lever Q is not connected directly with the sliding rod g, but operates the same through the intervention of a connecting lever-arm, k, pivoted at l in the support m.

The levers P and Q may be operated by the attendant to ship the belts onto the loose pulleys on the counter-shafts and stop the barbing-machine and the twisting and spooling machine; but by my invention this is done automatically without the intervention of the attendant, if there is any obstruction on the main wire or wires before entering the barbing-machine.

Upon a supporting-rod, R, is supported what I will call the "rocking lever-holder" S, prevented from moving endwise on said rod by collars n. The lever-holder S is so made that the levers P and Q press against the ends o o thereof when the power is applied and the machine is running properly, a spring, p, drawing the lever P and holding it against the holder

S, and a spring, q, in connection with a spring, r, serving to hold the lever Q and press it against the other side of the holder S, as clearly shown in the drawings. Said springs p and q are also for the purpose of drawing over the levers P and Q, to ship the belts onto the loose pulleys when the rocking lever-holder S is moved out of its position, to release the levers in the manner to be hereinafter described. In lieu of said springs weights may be used. A spring, s, interposed between the beam or plank d and the top of the holder S, and encircling the rod t, serves to keep the holder S in its proper position, as shown by full lines in the drawings, a check-nut, q', secured to the rod and above the beam d preventing the holder from being pushed down too far by the spring s. A cord or wire, u, is secured to the upper end of the rod t, the lower end of said rod being secured to the lever-holder S. Said cord u passes in this instance over grooved pulleys v v, and is secured at its lower end to an arm, T, hinged or pivoted in a suitable support, w, at the rear of the barbing-machine.

An angle-lever arm, U, provided in this instance with a cross-piece, x', with two guide-holes, y', therein at its upper end, and having a spring, z, attached to its lower end and to the floor, is pivoted and supported at the rear of the barbing-machine in a standard or support, V, in such a position that the lower end of the angle-arm U will rest upon the top of the arm T, as shown in Fig. 1, when the parts are in the position shown by full lines, Fig. 1.

Through the guide-holes y' in the angle-lever arm U, or in this instance in the cross-piece x', the main wires s' pass before entering the barbing machine, said holes being somewhat larger than the diameter of the wire, said wires and the spring z, which may be dispensed with, if desired, serving to keep the lever-arm U in its proper position (shown by full lines, Fig. 1) when there is no obstruction in or on the wire to prevent it from freely passing through the holes y' in said lever-arm U.

The operation of my automatic stopping device will be readily understood by those skilled in the art from the previous description, in connection with the drawings, and is as follows:

As long as there is no obstruction on or in the main wires to prevent them from passing freely through the guide-holes y' in the angle-lever arm U, and the machine continues to operate in a proper manner, the parts of my automatic stopping device will be in the position shown by full lines in the drawings; but as soon as there is an obstruction—for instance, a knot, a snarl, or a splice—in either one of the main wires which will not pass through the guide-holes y' in the angle-lever arm U, the machine, continuing to operate, will draw the wire or wires along, causing the lever-arm U to be drawn over into the position shown by dotted lines, Fig. 1, and at the same time causing the hinged arm T, upon which the lower end of the lever-arm U rests, to be drawn down, (see

dotted lines, Fig. 1,) pulling down the cord *u*, and drawing the rocking lever-holder *S* into the position shown by dotted lines, Fig. 1, releasing the levers *P* and *Q*. The springs *p* and *f*, then acting on said levers, draw them over, so as to ship simultaneously the belts *N* and *O* from the fast onto the loose pulleys on the counter-shafts, thus stopping the barbing and the twisting and spooling portions of the machine automatically.

I have described my invention, and shown it in the drawings, in connection with a machine for making barbed fencing; but I do not limit myself to this, as my invention may be used in connection with a machine for making plain wire fencing composed of two or more wires twisted together. It may also be used in connection with a machine driven by gear-connection, instead of by belt-connection, as shown.

In case the twisting and spooling portion of the machine is connected directly with the barbing portion of the machine, as in the Putnam Patent No. 187,776, before referred to, then only one belt-shipping device will be required to stop the machine, instead of two, as shown in the drawings.

I do not wish to limit myself to the special device for shipping the belt from the fast to the loose pulleys on the counter-shafts, as shown in the drawings, as any other well-known form of belt-shipping device operated by levers or their equivalents may be used in connection with my mechanism for automatically operating said levers to ship the belts and stop the machine without departing from the principle of my invention.

I do not wish to limit myself to the rocking lever-holder *S* described, for any equivalent device for holding the shipping-levers to be operated automatically may be employed.

Having described my improvements in apparatus for automatically stopping wire-fence machines, what I claim therein as my invention, and desire to secure by Letters Patent, is—

1. The combination, with a wire-fence machine and belt-shipping device, and lever for operating said shipping device, of a lever-arm provided with one or more guide-holes, for the purpose stated, pivoted at the rear end of the machine, and the hinged arm *T*, cord *u*, and rocking lever-holder *S*, constructed substantially as and for the purpose stated.

2. The combination, with pivoted lever-arm *U*, provided with one or more guide-holes, for the purpose stated, hinged arm *T*, cord *u*, and lever-holder *S*, of a belt-shipping device provided with an operating-lever, and with one or more springs to ship the belt automatically and stop the machine driven by said belt, substantially as set forth.

3. The combination, with a wire-fence machine and belt-shipping device having an operating-lever, and provided with and operated reversely by a spring, of lever-holder *S*, cord *u*, and hinged arm *T*, operated by the pivoted lever-arm *U*, provided with one or more guide-holes, for the purpose stated, in the manner substantially as shown and described.

4. The combination, with a belt-shipping device provided with and operated by a lever and a spring, of the lever-holder *S*, connected with and operated by a pivoted lever-arm *U*, provided with one or more guide-holes, for the purpose stated, so that at the proper time the lever-holder *S* will be automatically moved and the belt shipped to stop the machine, substantially as set forth.

5. The combination, with sliding rod *e*, spring *p*, loop *i*, and lever *P*, of rocking lever-holder *S*, rod *t*, spring *s*, cord *u*, hinged arm *T*, and lever-arm *U*, provided with one or more guide-holes, for the purpose stated, substantially as set forth.

JOHN D. CURTIS.

In presence of—

JOHN C. DEWEY,
FREDERICK W. SMITH.
